UNITED STATES PATENT OFFICE.

WILLIAM BOWIE AND JOHN BOWIE, OF GLASGOW, SCOTLAND.

CARPET-CLEANER.

SPECIFICATION forming part of Letters Patent No. 664,606, dated December 25, 1900.

Application filed January 21, 1899. Serial No. 702,881. (No model.)

To all whom it may concern:

Be it known that we, WILLIAM BOWIE and JOHN BOWIE, residing at 221 Strathdyde street, Bridgeton, Glasgow, Scotland, have 5 made certain new and useful Improvements in Carpet-Cleaners, (for which we have obtained patents as follows: in Great Britain, No. 15,005, dated July 8, 1898; in Germany, No. 108,012, dated January 12, 1899; in France, No. 284,966, dated January 7, 1899; in Belgium, No. 140,039, dated January 5, 1899, and in Canada, No. 63,087, dated May 18, 1899,) of which the following is a specification.

At present when cleaning carpets, rugs, &c., it is usual after they have been subjected to the beating or brushing process for the purpose of removing the dirt to renovate them by means of brushes charged with a detergent, which are vigorously rubbed over 20 the fabric by hand. This entails much labor and consumes a great deal of time.

The main object of our invention is to provide a machine whereby the carpet or other fabric can be renovated without the necessity 25 for hand rubbing. The machine is or may be also provided with means whereby the carpet can be steamed, if necessary.

In order that our said invention may be properly understood, we have hereunto appended 30 two explanatory sheets of drawings, which show a preferred mode of carrying out the invention.

Figure 1 is a front elevation of the machine. Fig. 2 is a view of one end of the machine, 35 and Fig. 3 is a view of the other end. Fig. 4 is a section of the machine, taken on the line $\alpha\alpha$, Fig. 1. Fig. 5 is a perspective view illustrating the construction of the end of the reciprocating frame.

40 In the drawings the same reference-letters wherever repeated indicate the same parts.

aa represent the frame of the machine and is formed of suitable uprights and cross-braces.

b is the machine-table over which the carpet to be cleaned and renovated is carried, 45 said table being supported on the frame aa .

The dotted line c , Figs. 2, 3, and 4, indicates the line of travel of the carpet.

d is the delivery-roller on which the carpet has been first rolled and from which it is 50 unwound when being cleaned.

e is the take-up roller, which is mounted on a shaft e' , having suitable bearings in brackets secured to the frame.

ff^2 represent the reciprocating frame carrying the brushes, and same is slidably mounted on ways supported by the frame at each end of the machine. The reciprocating frame consists of central end bars or blocks f , working in the ways at the ends of the machine, these 60 bars being connected by and supporting the separated brush - holding bars f^2 , between which latter the brushes engage. Any convenient manner of constructing the ends of the reciprocating frame may be employed— 65 such, for instance, as disclosed in Fig. 5 of the drawings—and as the same forms no part of the invention claimed it is not believed necessary to give a detailed description of the construction. 70

$g g$ are the brushes, which are secured to the blocks or handles h , said handles being held in the frame ff^2 by means of uprights f^3 , rising from the bars f^2 and carrying cross-heads f^4 , through which work depending 75 brush-supporting and adjusting screws f' .

$i i$ are benzene-troughs placed below the face of the table and provided with removable-hinged covers $l l$.

$k k$ are benzene-supply rollers, which are 80 partially immersed in the benzene j in the troughs.

m is a perforated steam-pipe running longitudinally along the center of the machine and below its face. This pipe m is divided 85 into two parts by a vertical partition at its center, so that steam can, as desired, be supplied at either one end or other of the machine, or to both ends.

$n n$ are branch steam-supply pipes leading 90 from the main steam-pipe o to the pipe m .

$p p$ are drain-pipes for drawing off water from the two parts of the perforated steam-pipe.

$q q$ are guide-rollers mounted on suitable 95 shafts, over which the carpet passes in traveling onto and from the table.

$r r$ are guides for the ends of the reciprocating frame f and are horizontally supported by suitable posts secured to the frame. 100

s is the main driving-shaft. $s' s'$ are fast and loose pulleys on this shaft s , and s^2 is a

belt for driving the fast pulley from a suitable overhead shaft.

5 $t' t'$ are pinions on each end of the shaft s , which gear, respectively, with cog-wheels $t t$ on each end of a secondary shaft t^2 .

$t^3 t^3$ are connecting-rods which are pivoted at one end to the wheels t and at the other end to the reciprocating frame $f f^2$.

10 $u u$ are eccentrics at each end of the shaft t^2 .

$u' u'$ are eccentric-rods, which at one end are connected to eccentric-straps working on the eccentrics u and at the other end to the upper end of levers u^2 , fulcrumed on the shaft e' of the roller e .

15 $u^3 u^3$ are ratchet-wheels keyed on the ends of the shaft e' .

$u^4 u^4$ are driving-pawls pivoted to the levers u^2 and engaging the teeth of the ratchet-wheel.

20 $u^5 u^5$ are stop-pawls pivoted to the frame a and also engaging the teeth of the ratchet-wheel.

v is a bevel-wheel at one end of the shaft d' of the roller d .

25 v' is a bevel-pinion on the shaft v^2 , gearing with the wheel v .

v^3 is a wheel with handle for rotating the shaft v^2 , by means of which the pinion v' is thrown in and out of gear with the wheel v .

30 w is a pulley on the shaft t^2 .

w' is an endless belt passing around the pulley w and around a small pulley on the end of the rear benzene-roller k .

35 x is a crossed driving-belt passing around the pulley x' on the extended end k' of the front benzene-roller k and also around a small pulley s^5 on the shaft s .

y is a fork pivoted at y' on the frame for shifting the belt s^2 .

40 z is a perforated plate arranged along the center of the table and above the pipe m , through the perforations in which the steam is forced into the carpet.

45 The operation is as follows: The carpet c to be cleaned, which is first wound upon the roller d by actuating the bevel-gearing $v v'$ and hand-wheel v^3 , is automatically unrolled from the roller d onto the roller e by means of the pawl and ratchet mechanisms $u^3 u^4$, ac-

50 tuated by the eccentric-rods u' . The carpet while being unrolled from the roller d and rolled up on the roller c is caused to gradually travel over the table b , and during such travel is subjected to the rubbing action of the brushes $g g$. At each forward reciprocation of the brush-frame the front row of brushes g comes in contact with the front benzene-roller k , while at each back reciprocation the rear row of brushes comes in con-

60 tact with the rear roller k . Thus one row of the brushes at each reciprocation comes in contact with the benzene-rollers k , which latter revolve in the benzene-troughs i , (the lids l of which are opened out, as shown in Fig. 4,) and as a consequence they lift a certain amount of the benzene from the rollers, which

at the next reciprocation is rubbed into the carpet. The action of the benzene, combined with the rubbing action of the brushes, effectively cleans and renovates the carpet.

70 It may be stated that the carpet is preferably beaten or shaken before being placed in the machine.

While the carpet is traveling over the table b , steam may be blown through it from the pipe m .

As will be seen from Fig. 1, there are three duplicate sets of brushes in the machine, arranged so as to suit the various widths of carpets. When a narrow carpet is being cleaned, 80 one set of brushes need only be used, and the other sets may be raised up by means of the screws f' , so as not to perform any work. By means of the screws f' the brushes can be raised and lowered in their frames f^2 , and 85 thereby adjusted so as to suit different thicknesses of carpet.

When one or other of the sets of brushes is not in use, the benzene-troughs opposite such set or sets may be closed by means of their 90 lids l . It may be further stated that the lids l when in the position shown at Fig. 4 prevent benzene being splashed about by the action of the brushes.

Whenever necessary, the pawls u^4 may be 95 thrown out of engagement with the ratchet-wheels u^3 by means of cords z' , which can be pulled upward, (these cords may pass over overhead pulleys and be provided with handles,) or by any other suitable and well-known 100 device.

Having now fully described our invention, what we claim, and desire to secure by Letters Patent, is—

1. In a machine for cleaning and renovating textile fabrics, the combination of a supporting-frame, brushes supported from the frame, mechanical means for reciprocating the brushes, means for traversing the fabric under the brushes, troughs supplied with a 110 fluid detergent supported by the frame, rollers revolving within the troughs and adapted to contact with the brushes, and means for revolving said rollers, substantially as described.

2. In a machine for cleaning and renovating textile fabrics, the combination of a supporting-frame, brushes supported from the frame, mechanical means for reciprocating the brushes, means for carrying the fabric 120 under the brushes, means for supplying a fluid detergent to the brushes, and means whereby steam can be directed against the fabric, substantially as described.

3. In a machine for cleaning and renovating textile fabrics, the combination of a supporting-frame, slides moving reciprocally on the frame, brushes carried by the slides and vertically adjustable thereon, means for reciprocating the slides, means for vertically 130 adjusting the brushes, a table arranged below the brushes, means for carrying the fabric

over the table and below the brushes and means for supplying a fluid detergent to the brushes, substantially as described.

4. In a machine for cleaning and renovating textile fabrics the combination of a supporting-frame, slides working reciprocally on the frame, brushes arranged in sections carried by the slides and vertically adjustable thereon, mechanical means for reciprocating the slides, means for vertically adjusting the brushes, a table arranged below the brushes and having a longitudinal opening therein, a perforated plate covering the opening in the

table, a perforated steam-pipe arranged below the said plate, means for traversing the fabric 15 over the table and below the brushes, and means for supplying a fluid detergent to the brushes, substantially as described.

Signed at Glasgow, Scotland, this 14th day of November, 1898.

WILLIAM BOWIE.
